UNITED STATES PATENT OFFICE

172,126

STEP STOOL

Mary Elizabeth Conhaim, Tulsa, Okla.

Application September 21, 1953, Serial No. 26,890

Term of patent 7 years

(Cl. D15—8)

To all whom it may concern:

Be it known that I, Mary Elizabeth Conhaim, a citizen of the United States, residing at Tulsa, in the county of Tulsa and State of Oklahoma, have invented a new, original, and ornamental Design for a Step Stool, of which the following is a specification, reference being had to the accompanying drawing, forming part thereof.

In the drawing:

Fig. 1 is a front elevational view of a step stool, showing my new design;

Fig. 2 is a side elevational view; and

Fig. 3 is a top plan view.

I claim:

The ornamental design for a step stool, as shown.
